UNITED STATES PATENT OFFICE.

ORATUS S. FRENCH AND JOHN W. MILLER, OF FREMONT, OHIO.

SPARK-ARRESTER.

No. 824,004.

Specification of Letters Patent.

Patented June 19, 1906.

Application filed December 19, 1905. Serial No. 292,416.

To all whom it may concern:

Be it known that we, ORATUS S. FRENCH and JOHN W. MILLER, citizens of the United States, residing at Fremont, in the county of 5 Sandusky and State of Ohio, have invented new and useful Improvements in Spark-Arresters, of which the following is a specification.

This invention is a spark-arrester, particularly adapted for use on traction-engines, although applicable to locomotives or stationary engines.

The arrester consists, broadly, of a series of pivoted plates which are arranged to lap each other and form baffles which prevent the passage of sparks.

The invention consists in the manner of constructing and mounting the plates and in the means for operating the same, as hereinafter described and claimed.

In the accompanying drawings, Figure 1 is a perspective view showing the invention, part of the boiler-shell being broken away. Fig. 2 is a perspective view showing the manner of connecting the plates to the operating-bar. Fig. 3 is a perspective view showing the sectional construction of the plates. Fig. 4 is a perspective view showing the operating mechanism. Figs. 5 and 6 are details in section and perspective of the locking mechanism for holding the plates as set.

Referring specifically to the drawings, the boiler-shell is indicated at 6, the stack at 7, and some of the boiler-tubes at 8. The construction shown is that of a traction-engine. For use on locomotives the spark-arrester will be placed in the smoke-box at the head of the boiler beyond the ends of the tubes.

At 9 are indicated two supporting-bars 40 which are secured to the boiler-shell on opposite sides thereof, as by bolts 10.

At 11 are indicated the series of plates forming the arrester. Each of these consists of a piece of angle-iron with the angle or flange 12 at the top. The plate has at the ends pivot-pins 13, which are mounted in holes in the bars 9, so that the plates may be turned and set at any angle desired. The two end plates are of double width or have extensions 14, which close against the boiler-tubes and the boiler-head, respectively, so as to close the large openings which would otherwise exist at such places.

The exhaust-nozzle which creates the draft

is indicated at 15 and extends up between 55 the plates, one or more being omitted on one side, the resulting space being closed by a plate 16.

By means of staples 17 the plates are loosely connected at their upper edges to a 60 bar 18, which extends above the same and by means of which the plates are swung simultaneously. This bar may be shifted in a number of ways, one of which is illustrated in the drawings, consisting of a lever-handle 19, 65 mounted upon a bracket 20 on the outside of the boiler-shell and connected by a rod 21, which extends through an opening in the bracket and in the boiler-shell to the bar 18. The rod 21 is notched, as at 22, to receive a 70 spring-catch 23, which works through a recess in the bracket 20. The extent to which the plates are opened or closed may be varied by raising or lowering the bar 21 and set as desired by engaging the catch 23 in the desired notch. For locomotive use the rod 9 will preferably be connected by suitable levers and connecting-rods to a hand-lever in the cab. 75

In use the plates of the arrester after the 80 fire is started are set a slight distance apart, and the draft will cause the cinders and sparks to strike the angles of the plates and be deflected without, however, unduly obstructing the draft and outlet for the smoke. 85

We claim—

The combination with a boiler having an upright exhaust-nozzle in the smoke-box thereof, of a spark-arrester comprising supporting-bars secured to the boiler-shell on 90 opposite sides thereof and extending horizontally along the same, a set of plates pivoted at their ends in the supporting-bars and extending horizontally entirely across the smoke-passage in the boiler under and around 95 the mouth of the nozzle which extends upwardly between the plates, a shifting bar extending lengthwise of the boiler across and above the plates and connected thereto, and means to shift the bar, to adjust the plates. 100

In testimony whereof we have signed our names to this specification in the presence of two subscribing witnesses.

ORATUS S. FRENCH.
JOHN W. MILLER.
